SPECIFICATION forming part of Design No. 34,684, dated June 18, 1901.

Application filed May 24, 1901. Serial No. 61,809. Term of patent 14 years.

To all whom it may concern:

Be it known that I, DAVID J. SEAMAN, a citizen of the United States of America, residing at South Bend, in the county of St. Joseph and State of Indiana, have invented and produced a new and original Design for Fabrics, of which the following is a specification, reference being had to the accompanying drawing, which forms a part hereof.

This design relates to the ornamentation of cotton, silk, woolen, paper, celluloid, and other fabrics.

The leading feature of the design is the representation of a man standing on the globe alternating with the representation of elks' heads having clock-faces at their throats.

The globe A is the symbolical representation of the earth, and standing at the top thereof appears the figure of a man having his arms outstretched and holding a hat in one hand. Alternating with the representation of the globe and the man are elks' heads B, having clock-faces C at their throats and having their horns D arching over the head of the man.
